SHIELDED SPARK PLUG

George M. Paulson, New York, N. Y., assignor to
The B. G. Corporation, New York, N. Y., a cor-
poration of New York

Application September 8, 1932, Serial No. 632,090

11 Claims. (Cl. 123—169)

The invention relates to spark-plugs which are shielded against the elements and oil, and it also more especially relates to spark-plugs which are shielded electrically to prevent the disturbances set up by the ignition current from adversely affecting radio equipment carried by the airplane or vehicle.

The invention is more particularly intended for aviation spark-plugs. In many airplane engines, other engine parts and accessories come so close to the spark-plugs that former shielded constructions are either unavailable or the application and removal of the shield would be very difficult.

15 An important object, therefore, of this invention is to provide a short or low, and compact, shielded spark-plug which occupies but little room outside the engine. A further object is to make it possible to apply and to remove the shield without removing the spark-plug and with the minimum of overhead clearance.

20 A further object is to provide for the tight and secure connection of the shield to the body of the spark-plug, and for its removal, in the most convenient manner, and also to permit the shield to be turned about the axis of the plug while the shield is in full engagement. An object is to provide a simple and effective type of connection between the shield and the plug, which makes it 25 possible to dispose a laterally entering conductor in any direction about the axis.

25 A further object is to provide a construction and manner of connecting the shield removably to the spark-plug such that when the shield is taken off the spark-plug can be treated like a regular spark-plug. A further object is to devise the part 30 of the connection which is carried by the spark-plug itself in such a way that it does not interfere in any way with the application of a wrench to the body of the plug, when a spark-plug is taken 35 out of the engine or put in.

Another object is to provide an improved manner of securing a shielded and insulated conductor to a spark-plug shield and for electrically connecting the conductor shielding to the metallic plug shield.

Another object is to provide the spark-plug shield with a terminal which automatically makes reliable contact with the top of the spark-plug 40 when the shield is inserted in place. A further object is to provide a spark-plug shield which does not have to be taken apart when applying it or removing it from the spark-plug.

Another object is to provide a spark-plug shield 45 of simple, durable and economical construction.

In former radio-shielded constructions the shields have been applied to the outside of the bodies of the plugs, or have been connected to the plugs by bails, or lock-nuts, or screw-threads or bayonet-type connections, which limit the conductor to one position or which cumber the spark-plug itself with attachments which are troublesome when it comes to replacing a spark-plug.

Briefly stated, a salient feature of this invention is that the connection between the shield and the spark-plug is brought down inside the "hex" of the body of the plug, thereby making possible the shortest possible construction. Another important feature is that the connection is made by a direct thrust of the lower end of the shield into 70 a socket in the top of the plug body, whereupon a resilient locking action takes place that holds the shield and the conductor in place without any possibility of loosening or coming apart, but permits the connection to be separated when desired. 75 The connection is also such as to be substantially or absolutely tight against water or oil.

Other objects and features of the invention will be apparent to those skilled in the art.

The parts and combinations of parts constituting the invention will be described and then pointed out in the claims.

In the accompanying drawings, forming part hereof:

Fig. 1 is a side elevation of a spark-plug, shield, and shielded conductor assembled, the illustration being of a preferred embodiment of the invention;

Fig. 2 is a vertical section;

Fig. 3 is a horizontal section taken on the line 3—3 of Fig. 2;

Fig. 4 is a horizontal section taken through the mid-portion of the shield; and

Fig. 5 is a fragmentary elevation showing the terminal construction which is located inside the 85 shield, the insulating bushing being in section.

The construction of the spark-plug proper, which is designated by the numeral 2, may be varied in numerous particulars without departing from the invention. Except for the matters 100 which will be pointed out, the construction illustrated is one that is known. The body 3 of the plug is the part that is screwed into and out of the engine opening. This part of a spark-plug is also frequently termed the shell. It has the 105 customary external screw-thread 4 on its lower portion to engage the engine opening, and at the top it has a polygonal portion 5 to take a wrench. In the spark-plug of the present invention, this portion is extended upward and made larger or 110

wider than is ordinary. The mid-portion of the body has an internal screw-thread to receive a nut 6, which is screwed into the body from the top. This nut is a preferred element or means for holding the core in the body and also for producing a gas-tight joint between the spindle and the surrounding rolled mica insulation 7. The term "core" may be used for convenience as including the spindle as well as the insulating portions of the spark-plug proper. The particular construction shown is one in which a stack of mica washers 8 is held under compression between the head 9 at the lower end of the spindle and a compressible metal sealing ring which is forced upward in a tapered opening of the nut 6, another stack of mica washers 10 being held under compression between the top of the nut and an upset retaining means at the top of the spindle. This part of the core extends above the body of the plug in the usual manner. In place of the customary top button against which the upper end of the spindle is usually upset, I provide the plug for the purpose of this invention with an electrical terminal comprising a beveled annulus 11, shaped to an outwardly and downwardly sloping contact face 12, which extends entirely around the annulus. This face is preferably concavely curved in any vertical axial plane, as shown.

As previously stated, the "hex" 5 of the body is made wider than usual. It also extends somewhat above the nut 6, whereas ordinarily the nut projects above the shell. A very important new feature is that the hex or top of the body is made with a broad internal recess 14, the boundary wall of which is spaced away from the core, and, in this construction, away from the hex top 15 of the nut, the interior of the recess being, therefore, much wider than the internal, threaded portion of the body which receives the nut. The ample width of the recess 14 permits the nut to be engaged by a socket wrench when the spark-plug proper is assembled, or in case it should be necessary to take the plug apart. In any event the boundary wall of the recess should be sufficiently spaced from the core or other internal parts extending upward into and through the recess so that the shield 16 can be applied and removed without interfering with any such parts.

The shield 16 is preferably a squat ball-like shell, made of two sheet metal parts permanently united by a joint 18 at approximately the mid-horizontal plane. A metal connection thimble 19 is held firmly at 20 in an opening in the shield. This thimble extends laterally from the shield, but by "laterally" it is not necessarily meant that the thimble is disposed at right-angles to the axis of the spark-plug, as it is shown, since it may also be disposed at an upward inclination.

The bottom of the shield is formed with a short neck 22 of such diameter that it can be forced within the bounding wall of the recess or socket 14 of the body of the spark-plug 2. This neck is subdivided by numerous vertical slits 23, to form many resilient fingers 24. The lower ends of these fingers are crimped outward in the shape of a rounded bead 25, to snap or spring into a circular groove 26 in the lower portion of the bounding wall of the socket 14. The form of the locking elements 25 makes it possible to enter them in the top of the socket by a direct push on top of the shield. As the fingers enter they are squeezed inward, and when the shield is all the way home, they spring outward into locking engagement with the groove. The lock is a tenacious one, but notwithstanding this, the shield can

be removed without undue effort. The resilience of the metal of the fingers could be relied upon solely for the locking action, but after numerous applications and removal of the shield they would tend to lose their springiness. To overcome that difficulty, I have provided a spring wire 28 curved to form a split ring, which is sprung into the discontinuous internal groove formed by the beads of the fingers 24. This spring wire, thus held, requires no other means to keep it from coming out when the shield is off the plug, and it greatly prolongs the useful life of the fingers.

It will be understood that the importance of a secure lock between the shield and the spark-plug is not merely to keep the shield from getting loose or becoming accidentally detached, but to preserve the electrical connection between the wire 29 of the conductor 30 and the central electrode of the spark-plug, and to also preserve the electrical shielding connection between the metallic shielding 32 of the conductor, through the metal shield 16 to the grounded body of the spark-plug.

From the foregoing it will be evident that the invention provides a very short shielded spark-plug construction, and one in which the shield can be taken off and put on with but little headroom. Because of the flexibility of the neck or fingers of the shield, the neck can be cocked or tilted when the snap-lock is not actually in engagement. Thus, the shield can be taken off by a rocking movement when the projections 25 have been pulled out of the groove 26, and the neck can be entered in a similar manner, if it should be found more convenient to avoid obstruction in this manner.

The construction also permits the shield to be applied in any position of rotation about the axis, or to be turned to any position desired after it is securely locked, in order properly to orient the lateral conductor. Strength, simplicity, reliability, flexibility, cheapness and convenience of the means for detachably assembling the shield and the spark-plug are objects that have been sought. When the shield is in place it is virtually one with the spark-plug, and when the shield is removed the spark-plug proper is left as its own unit and can be dealt with like an ordinary spark-plug. The spark-plug itself has no extraneous devices, and can be taken out of the engine and put in, and can be assembled and disassembled, as easily as an ordinary spark-plug.

The large "hex" section 5, which is extended upward from the body of the spark-plug around the core to provide a socket for the reception of the neck of the shield, has a further advantage, which is that it gives additional radiating surface and helps materially to cool the plug.

The conductor 30 is of a known kind having insulation 31 about the wire, a metallic braided shielding 32 about the insulation, and a fabric braiding 33 over all. The cable is prepared by cutting the outside fabric back a considerable distance from the end of the wire, cutting the metallic shielding 32 back a shorter distance from the end, and cutting away the insulation so that a short portion 34 of the wire is left projecting.

The portion of the insulated conductor from which the braidings have been removed is inserted through the connection thimble 19 and through an insulating bushing 36, which is held in the thimble and projects into the interior of the shield.

The automatic contact-making terminal of the shield, constituting an important feature of

the invention, is preferably contrived in the following manner: An apertured disc 38 is sprung into a groove in the bore of the bushing 36, near its inner end. A small metal collar 39 is held in

5 the aperture of this disc, projecting forward. The projection 34, of the stranded wire is passed through this collar and its strands are bent back over the forward end of the collar to establish electrical connection between the conductor and the collar. This is sufficient to insure good connection at this point, but naturally additional means may be used if desired.

10 The terminal proper is formed of a piece of resilient wire closely coiled to form a head 40, preferably of a somewhat conical shape, to make good contact with the face 12 of the annulus 11 as the result of merely pushing the shield 16 into engagement with the body of the spark-plug. A limb 41 of this terminal extends rearward from 15 the head and is given a turn about the collar 39, between the disc 38 and a flange 44 on the collar. By upsetting the rear end of the collar against the back of the disc, the collar is secured in place and also the limb of the terminal is anchored.

20 25 The manner of securing the conductor and of making electrical connection between the shield 16 and the shielding 32 of the conductor remains to be described.

The outer end of the connection thimble 19 is 30 screw-threaded on the outside to receive a coupling nut 46. On the inside, this end of the thimble is formed with a tapered recess 47. The cut-back end of the metallic braiding 32 is turned back over a tapered wedge ring 48, which is forced by 35 the nut 46 into the tapered recess, thereby strongly gripping the metallic braiding to the metal thimble and likewise firmly holding the conductor so that it can not pull out.

While the preferred embodiment of the invention has been described in detail, it will be understood that many changes in form and detail may be made without altering the substance of the invention or particular features thereof.

40 It may be stated that the sparking points or 45 grounded electrodes 50 and the central electrode 51 are of novel construction, but since these are claimed in a separate application it is unnecessary to describe them here.

I claim:

50 1. The combination with a spark-plug the body of which is so formed as to provide a rigid socket in its top, of a sheet metal shield having an entering neck constructed for rotary, resilient, separable, interlocking engagement with said socket.

55 2. The combination with a spark-plug having a body, the top of which is formed with a socket having a circular groove, of a shield having a socket-entering portion subdivided into resilient fingers which are provided with formations to interlock removably with said groove.

3. The combination with a spark-plug having a body, the top of which is formed with a socket having a circular groove, of a shield having a socket having a circular groove, of a shield having a socket-entering portion subdivided into resilient fingers which are provided with formations to interlock removably with said groove, and a resilient element swung into all said formations to give life to the fingers.

70 4. A spark-plug having a body, the lower portion of which is externally threaded to engage the engine opening, the middle portion of which is internally threaded to receive a nut, and the upper portion of which is externally polygonal to 75 take a wrench, this polygonal portion having a

wide recess to form a socket for a detachable shield, the bounding wall of said recess being much larger in diameter than the threaded interior of the body below the recess.

5. A spark-plug having a body, a spindle, insulation about the spindle, and a beveled annulus about the upper end of the spindle, which is upset to grip said annulus against the top of the insulation, the top of said body being formed with a recess, in combination with a shield having means to receive a laterally entering conductor, and a resilient terminal within said shield to make automatic contact with said annulus when the lower end of the shield is inserted in said recess. 80

6. A spark-plug shield comprising a metallic shell having a neck at the bottom adapted to engage a socket in the body of the spark-plug, a lateral connection thimble of conducting material held in an opening of said shell, an insulating bushing in said thimble and projecting into the hollow interior of the shell, said bushing adapted to receive an insulated conductor, and a terminal comprising a coiled head and a resilient limb, the latter secured in the bushing. 90

7. A spark-plug shield comprising a metallic shell having a neck at the bottom adapted to engage a socket in the body of the spark-plug, a lateral connection thimble of conducting material held in an opening of said shell, an insulating bushing in said thimble and projecting into the hollow interior of the shell, said bushing adapted to receive an insulated conductor, a small metal collar held in the inner end of said bushing and adapted to receive the bare portion of the conductor, and a resilient wire terminal 100 secured to said collar and having a coiled head. 105

8. A spark-plug shield comprising a metallic shell having a neck at the bottom adapted to engage a socket in the body of the spark-plug, a lateral connection thimble of conducting material held in an opening of said shell, an insulating bushing in said thimble and projecting into the hollow interior of the shell, said bushing adapted to receive an insulated conductor, an apertured disc fixed in the inner end of said bushing, a small metal collar projecting from said disc, and a resilient, coil-headed terminal, said collar being upset to grip the collar and the limb of said terminal to said disc. 115

9. The combination with a spark-plug, of a metal shield applied to the metal body of the spark-plug, said shield having a connection portion which is externally threaded and formed internally with a tapering socket, an insulated conductor inserted in said connection portion and having a metallic shielding, a nut to engage the external threads of said connection portion, and a tapered annular wedge forced into said tapered recess to grip a turned-back portion of the said metallic conductor shielding and to secure the 125 conductor in said connection portion. 130

10. A radio-shielded spark-plug, comprising a spark-plug having a body and a core, said body having an enlarged wrench-receiving portion which is recessed to form a rigid socket surrounding and spaced from the core, and said core extending above said socket and provided at the top with a terminal, in combination with a shield comprising a metal shell enclosing and extending over the upwardly projecting portion of the 140 core and having means to receive a laterally entering conductor, said shell having a bottom neck to fit within said socket in electrical contact with the body of the spark-plug, said neck being resilient and the neck and socket being so 145 150

formed as to constitute a swivel connection, outward pressure of the neck locking it detachably in swivel engagement with the socket, and a resilient terminal firmly supported in the shell in electrical connection with the conductor and insulated from the shell and adapted to make electrical contact automatically with the terminal of the spark-plug when the neck of the shell is thrust into the socket.

10 11. A radio-shielded spark-plug, comprising a spark-plug having a body and a core, said body having an enlarged wrench-receiving portion which is recessed to form a socket surrounding and spaced from the core, and said core extending above said socket and provided at the top with a terminal, in combination with a shield comprising a metal shell enclosing and extending over the upwardly projecting portion of the core

and having means to receive a laterally entering conductor, said shell having a bottom neck to fit within said socket in electrical contact with the body of the spark-plug, said socket and neck being provided with a circular groove and resilient portions to engage the same so as to constitute a detachable and swiveling connection, said shield having a lateral opening, a metal thimble secured to the shell at said opening and adapted to be electrically connected with the metal-shielding of an insulated conductor, a rigid insulating bushing in said thimble for the reception of the conductor, and a resilient terminal carried by said bushing and adapted to make contact automatically with the terminal of the spark-plug when the neck of the shell is thrust into the socket.
